COMBINED FLASK AND COVER THEREFOR

Robert D. Hagert and James L. Sunderson, Boulder,
Colo., assignors to Bota of Boulder, Boulder, Colo.

Filed Apr. 30, 1973, Ser. No. 355,746

Term of patent 14 years

Int. Cl. D9—01

U.S. Cl. D9—63

FIG. 4

FIG. 5

FIG. 6

FIG. 7

FIG. 1 is a front perspective view of a combined flask and cover therefor showing our new design;

FIG. 2 is a side elevational view;

FIG. 3 is a front elevational view;

FIG. 4 is a bottom plan view;

FIG. 5 is a top plan view;

FIG. 6 is an elevational view showing the side opposite that seen in FIG. 2; and

FIG. 7 is a rear elevational view thereof.

We claim:

The ornamental design for a combined flask and cover therefor, as shown.
